AUTOMATIC SHINGLE SHAKE FORMING MACHINE

Lee B. Dennison, Fernwood, Idaho

Application September 24, 1948, Serial No. 50,953

5 Claims. (Cl. 144—13)

1

This invention relates to an automatic machine for treating the surface of or grooving shingles to produce what is commonly referred to as "shake shingles."

A primary object of this invention is to automatically feed conventional wedge-shaped shingles to a cutter, whereby the surface of the shingles will be grooved or provided with longitudinally disposed corrugations to produce shake shingles.

Another important object of this invention is to provide a guide plate for a shingle, the guide plate being hinged to the frame and tiltable downwardly and upwardly relative to the rotary cutter, adjustment of the cutter being responsive to means engaged by and actuated by the shingle moving over the surface of the plate.

And yet another important object of this invention is to provide a shingle planing machine which is compact and simply and practically constructed and which will groove tapered shingles at a uniform depth throughout their length, the machine functioning automatically after a shingle has been placed thereon to feed the shingle in engagement with the cutter head and thus form grooves therein and to discharge the planed shaped shingles.

A meritorious feature of this invention resides in the provision of a frame, having an automatically operated and controlled feeding device for feeding a shingle into and through the machine, a cutter head having a plurality of scalloped knives radially extending therefrom for grooving the lower surface of the shingle as it is fed over the cutter head, and a control device which is operated by the movement of the shingle and which functions to lower the surface of the shingle into engagement with the scalloped knives.

These and ancillary objects and other meritorious features are attained by this invention, a preferred embodiment of which is set forth in the following description and illustrated in the accompanying drawings, wherein:

Figure 1 is a side elevational view of a machine constructed in accordance with the principles of the instant invention;

Figure 2 is a fragmentary vertical sectional view of the feeding, cutting and mechanical table trip construction;

Figure 3 is a top plan view of this invention;

Figure 4 is a top plan view, with the automatically operated table feeder and mechanical table trip removed, to illustrate the cutter head and blade structure;

Figure 5 is a side elevational view of the instant invention;

Figure 6 is a sectional view taken on the line 6—6 of Figure 1; and

Figure 7 is a view in perspective of the grooved shake shingle which is formed by the machine illustrated in the foregoing views.

Referring now more particularly to the drawings, this invention comprises a frame consisting of opposed parallel base members 12, from which extend upwardly at opposite ends thereof a pair of opposed standards or posts 14 and a similar pair 16. The opposed standards 16 extend upwardly beyond the terminating point of the standards or posts 14 and have secured thereto opposed side members 18 and 20 which extend longitudinally therefrom and are disposed at their opposite ends on the upper ends of the opposed standards 14. Transverse bars or end members 22 and 24 are disposed between the opposed ends of the side members 18 and 20. A top or shelf 26 is secured at one end to the top or upper end of the transverse bar 24 and projects forwardly therefrom relative to the transverse bar 22. The shelf 26 terminates in a downwardly beveled free or unattached end, disposed adjacent to but spaced inwardly from the end bar 22. A pair of transversely spaced openings or slots 28 are provided in the shelf, adjacent the free end 30 thereof, for a purpose to be later described. The upper surface of the shelf or top 26 serves as a discharge point for the finished or planed shingle, as will become later apparent.

A conventional electric motor 32 is bolted as at 34 to a supporting base or shelf 36, the latter being transversely disposed on the opposed base members 12. Of course, the motor is provided with a conventional armature or driving shaft 42, the same extending outwardly beyond the frame and having adjacent pulleys 38 and 40 keyed thereon.

A shaft 44 is transversely disposed between the opposed frame standards 16 and rotatably mounted on the outer edges thereof by means of a pair of bearing brackets or collars 46 and 48, the latter being bolted as at 50 to the post standards or legs. A pulley wheel 52 is fixed on one end of the shaft 44 and is connected with the driving shaft 42 of the motor through a belt 54 connected to the pulley 38. A pair of opposed longitudinally extending angle irons 56 and 58 are provided at one end with bearing sleeves 60, the same being disposed on the shaft 44, the shaft 44 thus serving as a pivot point for the opposed angle members which are connected by transverse slats or members 62 and 64. A feeding roller 66, having a roughened outer surface for abrading or roughening one side of a shingle

and for feeding the shingle through the machine is journaled to the free or unattached end of the angle irons 56 and 58, as seen in Figures 1 and 3. The feeding roller 66 is, of course, provided at its opposite ends with extending spindles 68 and 70, the spindle 70 being journaled in a journal box 72 mounted to the under surface of the angle iron 56, the spindle or shaft 68 being disposed through a similar journal box 74 bolted as at 76 to the underside of the extended end of the angle iron 56. A pulley 78 is keyed or otherwise affixed to the extending end of the shaft 68 and is connected to a smaller pulley 80 secured on the extending end of the shaft 44 by means of a belt 82.

Means is provided for automatically and adjustably maintaining the rotary feed roller 66 in engagement with the unattached end of the top 26, in front of the transverse slots or openings 28. The means preferred comprises a lever 84 terminating in a hook at 86, the lateral extension or hook end 86 being disposed in a slot 88 formed in the angle iron 56, as seen in Figure 1. The opposite end of the lever is pivoted as at 90 to an arm 92 which is pivoted as at 94 to one of the opposed base members 12. The arm 92 extends beyond the frame and a weight 96 is slidably and detachably associated therewith. Thus, weight on the extending end of the arm 92 holds the same down and exerts a pressure on the hook extension 86, which engages the angle iron 56 and holds the same in a slanted position. The positioning of the angle iron 56 and the angle iron 58 maintains the feed roller 66 in engagement with the top 26, for a purpose to be later described.

A cylindrical cutter head or roller 98 is rotatably journaled in journal boxes 100 and 102, the journal boxes being disposed on the opposed longitudinal side members 20 of the frame, adjacent the end 30 of the top 26 and in vertical alignment with the extending ends of the angle irons 56 and 58. A pulley 104 is disposed on the extending shaft end of the cutter head and is connected with the pulley 40 by means of a connecting belt 106, so that the cutter head is rotated through the operation of the motor 32, correspondingly the motor actuating the feeding roller 66. A plurality of knives 108 are transversely disposed in the cutter head and angularly extend therefrom in spaced fashion, as seen in Figure 1. The knives are grooved on their beveled sides and straight ground on the face, so that the knives represent conventional scalloped knives, as is best illustrated in Figures 3 and 4.

Means is provided for admitting a shingle into engagement with the feed roller 66 and in conjunction therewith for lowering the undersurface of the shingle into engagement with the cutter head 98 and the knives carried thereby. In this respect, a rod 110 is transversely journaled between the upper edges of the opposed side members 20, the rod having its extremities rotatably journaled in bearing plates 112 which are bolted as at 114 to the top edge of the respective side members. A plate or bed element 116 is secured on the rod between the bearing plates 112 and is provided with opposed angular side flanges or walls 118 and 120. The plate 116 is disposed on the rod off-center, so that the major portion of the plate is disposed rearwardly of the rod, as seen in Figure 1. An angle iron 122 is secured to the transverse bar 22 and a bolt 124 is disposed in the horizontal section of the angle iron with a locking nut 126 being provided. The bolt 124 is

vertically adjustable and defines a stop for the rearward or major portion of the plate, as seen in Figure 1.

The plate is adapted to guide a shingle 128, having a tip end 130 and a butt end 132 into engagement by the cutter head and the knives carried thereby. In this respect, the tip end is first inserted on the plate and moved manually relative to the feed roller 66, which grips the upper surface of the shingle and roughens or abrades the surface. The feed roller also moves the shingle inwardly and means is provided for tilting the plate to a horizontal position, so that the under surface of the shingle is disposed in the cutting path of the cutter head. The means is preferably engaged by and actuated by the tip of the shingle, as the same is moved inwardly of the frame by the feed roller. In this respect, a transverse rod or shaft 134 is journaled in the side members 18, 20 beneath the top or shelf 26 in vertical alignment with the slots 28 in the top 26. A pair of spring bars 136 and 138 are coiled at one end around the shaft 134 and have their opposite ends extended upwardly through the respective slots 28 and terminating above the plane of the top 26 and rearwardly of the feed roller 66. A rod 140 is journaled transversely in the side members 18, 20, having one end 142 extending beyond one of said members, as seen in Figure 6. A rigid bar or actuating finger 144 is disposed on the rod 140 and extends upwardly and outwardly therefrom. The upper end of the actuating finger 144 is suitably apertured to receive an operating rod 146 slidably disposed therein. The operating rod 146 is similarly disposed through a bar 148 which extends upwardly from a collar 150 secured on the rod 134, as seen in Figure 4. Of course, complementary stop plates or adjusting nuts 152 are disposed on the rod 146 to lock the bar 148 in the desired adjusted position thereon, with a similar pair of complementary locking stop plates 154 provided for engagement of the actuating finger 144. A wedge 160 is formed integrally on the under surface of the plate 116 and disposed in engagement with the end of the actuating finger 144. A spring 162 terminating in hook ends 164 and 166 is disposed between the actuating finger 144 and the end member 22 of the frame. In this respect, a ring 168 is formed on the bar 144 to be engaged by the hook terminal 166 of the spring, while a ring 170 is adjustably inserted through the end member 22 to be engaged by the hook end 164 of the spring. The hook 170 is provided with an elongated externally threaded shank 172 which projects through and beyond the frame member 22 and is adapted to receive a wing nut 174.

A collar 176 is formed on the extending end of the rod 134 and is provided with a flexible bar or spring bar 178 having its opposite end disposed on the extending end 142 of the rod 140.

The operation of this device is believed very simple and is as follows:

A shingle 128 is previously formed in any conventional or desired manner and is so formed with a butt end 132 and a tip 130. The shingle is laid on the plate or guide bed element 116 and the tip is moved into engagement by the feed roller 66. As the feed roller is rotated through the motor 32 and the belt transmission system, the shingle is moved inwardly until the tip moves against and engages the extending ends of the spring bars 136 and 138. As the tip abuts against the ends of the spring bars, the spring bars are

moved rearwardly causing the bar 148 to move rearwardly and moving the connecting rod 146 accordingly. As the connecting rod 146 moves, the actuating finger 144 is correspondingly moved onto the beveled surface of the wedge block 160 until the tip or end of the actuating finger is completely moved off of the wedge block 160. At this time, with reference to Figure 2, it will be seen that the guide bed element will be disposed in a horizontal position and the under surface of the shingle will be disposed in the cutting area of the cutting head. As the cutter head rotates and the shingle is moved inwardly on the top or shelf 26 by the feed roller, the scalloped knives are brought into engagement with the under surface and form longitudinal grooves or corrugations in the under surface, as seen in Figure 7. Thus, a weather side is imparted to the shingle in a convenient and efficient manner. After the butt end of the shingle is moved past the cutting area, the spring bars are urged to their normal position in the slots 28 by the spring 162. However, the movement forwardly of the spring bars is limited by engagement of the spring 178 on the end 142 of the rod 140. Accordingly, the machine is now ready for successive planing operations.

It is to be especially apparent that the shingle is maintained between the top 26 and the feed roller 66 by exerting a downward pressure on the roller 66 through the medium of the lever 84 and the weighted arm 92. Of course, the position of the spring bars can be easily adjusted by adjusting the tension on the spring 162 by means of threaded shank 172 and wing nut 174.

Thus it can be seen that there is provided a compact machine, which can be easily set up at the building site and can be efficiently and conveniently operated to produce a large number of shake shingles in a short period of time, and with but a slight expenditure of labor being required.

However, since many other modifications and purposes of this invention will become readily apparent to those skilled in the art upon a perusal of the foregoing description, it is to be understood that certain changes in style, size and components may be effected without a departure from the spirit of the invention and within the scope of the appended claims.

Having described the invention, what is claimed as new is:

1. A shingle grooving machine comprising a frame, a power driven rotary grooving cutter journaled in said frame transversely thereof, a guide plate at one side of the cutter for supporting a shingle to be manually fed thereon initially over said cutter and pivotally mounted on said frame for tilting upwardly away from said cutter and being tilttable downwardly toward said

cutter under the weight of a shingle fed thereover to lower said shingle into engagement with said cutter, power driven shingle feed means on said frame on the other side of said cutter to which the shingle is manually fed initially for subsequent power feed of the shingle over the cutter, releasable means normally holding said plate tilted upwardly, and means operative by the shingle as it is fed by said feeding means to release said releasable means so that said plate may tilt downwardly.

2. A shingle grooving machine according to claim 1 wherein said plate is overbalanced to normally swing upwardly as soon as the shingle is fed off the same.

3. A shingle grooving machine according to claim 1 wherein said last named means comprises a rock shaft journaled transversely in said frame, a pair of swingable shaft rocking fingers upstanding from said shaft at said other side of the cutter and projecting into the path of feed of the shingle being fed by said feeding means for engagement by said shingle to swing the fingers, and operating connections between one of said fingers and said releasing means.

4. A shingle grooving machine according to claim 1 wherein said releasable means comprises a member on the bottom of said plate, and an upstanding finger pivoted on said frame and supporting said member and swingable out of supporting relation to said member.

5. A shingle grooving machine according to claim 1 wherein said shingle feeding means comprises a feed roller above said frame for pressure engagement with the shingle, a pair of arms carrying the roller between corresponding ends thereof and pivotally mounted on said frame for downward swinging to engage said roller with the shingle, and means to exert downward pressure against at least one of said arms comprising a hooked lever engaging one of said arms, a pivoted arm on said frame to which said lever is pivoted, and a counterweight on said last named arm.

LEE B. DENNISON.
